(57) CLAIM

The ornamental design for a sport team candle, as shown and described.

DESCRIPTION

FIG. 1 is a perspective view of a sport team candle showing my new design;

FIG. 2 is a site view thereof; opposite side view is a mirror image thereof;

FIG. 3 is a front view thereof;

FIG. 4 is a back view thereof;

FIG. 5 is a top view thereof;

FIG. 6 is a bottom view thereof; and,

FIG. 7 is a cross-sectional view thereof.

In FIG. 2, the broken lines showing the environmental structure for purposes of illustrating the sport team candle in a condition of use. The broken lines and the structure they depict form no part of the claimed design.

1 Claim, 6 Drawing Sheets
